UNITED STATES PATENT OFFICE.

CHARLES F. H. FRANKE AND FREDERICK BUCHHORN, OF CHICAGO,
ILLINOIS.

SELF-CLEANING FILTER.

SPECIFICATION forming part of Letters Patent No. 593,573, dated November 16, 1897.

Application filed January 11, 1897. Serial No. 618,892. (No model.)

To all whom it may concern:

Be it known that we, CHARLES F. H. FRANKE and FREDERICK BUCHHORN, citizens of the United States, residing at Chicago, in the 5 county of Cook, State of Illinois, have invented an Improvement in Self-Cleaning Filters, of which the following is a specification.

For a complete description of our invention reference is made to the accompanying drawings, forming a part of this specification, and in which—

Figure 1 is a complete sectional view showing all parts. Fig. 2 is a horizontal view, part in section. Fig. 3 is an elevation of our 15 improved collar for clamping the filter to the faucet. Fig. 4 is a plan of the same. Fig. 5 is a horizontal section of the waste-outlet of our filter, taken on the line $\alpha\alpha$ and looking in the direction of the arrow. Fig. 6 is an 20 elevation of the valve of our filter and its controlling-spring. Fig. 7 is an elevation of the thumb-ring for controlling said valve, and Fig. 8 is a plan of the same.

Our invention has for its object the production of an efficient self-cleaning filter of 25 simple and durable construction.

A further object is to provide a means for clamping the filter to a faucet or pipe of any size without screw-threading or otherwise 30 altering the nozzle of said pipe or faucet.

The outer casing of our filter is composed of the parts A, B, and C. The parts B and C are preferably of brass, turned or spun out in such manner as to fit snugly over 35 the cylindrical tube A, of similar material. Through the center of this casing passes a metallic tube H, having near its upper end a shoulder engaging on the upper edge of the centrally-disposed hole in the piece B.

C' is a ring fitting into the enlarged portion 40 of the cup-shaped piece C and having lugs c c projecting from its inner periphery. Attached to these lugs by the screws b b is a rod D, having an opening in its center, said opening being screw-threaded to receive the lower 45 end of the above-mentioned tube H. Between the cylindrical piece A and the upper part of the case B is a thin washer q, of rubber. Fitting in the annular groove formed between 50 the outer periphery of the piece C and the

inner periphery of the ring C' is a similar rubber washer o. When the tube H is screwed firmly into the opening in the rod D, all of the parts herein described are bound firmly together and all the external joints are rendered tight by virtue of the rubber washers q and o. Resting against the inner side of the washer q is a metallic ring E, on the lower side of which is fastened a screen L of fine-wire gauze, through a hole in the center of 55 which passes the tube H. On the lower side of this gauze screen is placed a washer Q' of thin silk cloth.

Above the rod D is a leaf-spring R, which surrounds the tube H and bears against the 60 rod D on its lower side and against a plate P, of brass, on its upper side. This plate of brass has an annular depression near the circumference of its upper face in which rests the washer r, preferably of soft rubber. This 65 washer projects beyond the edge of the plate and bears against the inner surface of the cylindrical shell A. The plate P is perforated 70 with holes h, tapering from above. On the upper side of the plate P is placed another 75 screen L', of wire-gauze, also covered by a washer Q of silk cloth. In the space between the upper and lower screens of wire-gauze and their corresponding coverings of silk cloth is placed the filtering medium X, consisting, 80 preferably, of raw cotton, but may consist of sand, charcoal, porous stone, spun-glass, wool, or any other suitable material. We have found by careful experiments that raw cotton or cotton which has not been treated in 85 such manner as to remove its natural oil is the most desirable substance for this purpose, as it not only filters well, but will last for years without rotting.

The leaf-spring R, pressing against the under side of the plate P, tends to force it upward and thus maintain the filtering medium in a suitably-compact condition. The function of the silk washers above and below the filtering medium is not only to aid in filtering, but to keep the small particles of the filtering medium from working loose and becoming lost.

The valve V is normally held by the spring S in a position just above the valve-seat, which 90

is in the upper part of the tubular extension N, projecting from the bottom of the case C. The thumb-ring K is clamped to the lower tubular portion W of the valve V by the screws s's'. By pulling the thumb-ring K down the valve V is caused to rest in the valve-seat and thus completely close the opening in the shell C. The strength of the spring S is such as to raise the valve when it is not subjected to pressure from above by the water in the filter, but to allow it to remain closed as long as the water-pressure exists in the filter.

The clamping-sleeve G has two lugs l l projecting from its upper end, and between these lugs is a vertical slot. A screw s passes through a hole in one of these lugs and engages a threaded hole in the other in such manner as to contract the diameter of the upper part of the ring when tightened. A slot T is cut at right angles to the axis of the sleeve in such manner as to afford greater flexibility between the lugs l l. The lower portion of the sleeve is screw-threaded on its outer surface. This screw-thread may be made to engage with a corresponding thread on the inner portion of the enlarged part of the tube H of the filter.

To attach the filter to faucet F, the sleeve G is slipped over the nozzle of the faucet in such manner as to allow the lower edge of the faucet to project slightly below the ring. It is then firmly clamped by means of the set-screw s. The filter may then be screwed in place, the joint being rendered water-tight by a rubber washer p, resting in the bottom of the enlarged portion of the tube and against the under side of the projecting portion of the faucet.

The operation of our filter is as follows: When the water is turned on through the faucet, it rushes down through the tube H, around the valve V, and out through the tubular opening N. It will continue to take this path until the ring K is manually pulled down, when the valve is closed and the water forced to take another path. The water is now forced upward through the openings h in the plate P, through the filtering medium X, and into the chambers above, from which it escapes by the tube or nozzle U. The valve V is held closed by the water-pressure as long as the water is turned on from above. As soon, however, as the water is turned off the spring s opens the valve and all the water contained in the filter is allowed to escape through the lower opening. This rush of water which follows the opening of the valve V carries with it the residue collected on the under side of the filtering medium X and allows it to drain from the lower chamber. The draining off of the water in the filter causes a downward suction of air through the nozzle U and the filtering medium X, effectually driving out any sediment that may have worked slightly into the lower portion of the medium X. When the water is again turned on, the first rush

of water through the lower chamber D completes the washing out of this chamber.

It has been found that where a filtering medium is inclosed in a vessel having smooth walls a comparatively open path is formed between the wall of the vessel and the filtering medium which often allows dirt and other foreign matter to pass through the filter. The rubber washer effectually prevents the forming of such a path, and thus entirely avoids this difficulty.

The strength of the spring S may be so adjusted as to admit of the automatic closure of the valve by the water-pressure itself, thus dispensing with the thumb-ring and making the action of the valve entirely automatic. This and many other modifications clearly come within the scope of our invention.

Having now fully described our invention, what we claim as new, and desire to secure by Letters Patent, is—

1. A self-cleaning filter comprising a hollow metallic case containing a filtering medium, a tube leading from the water-supply to a chamber below said filtering medium, a tube for filtered water leading from said case above said filtering medium, a tubular opening leading from said case below said filtering medium, a valve having a hollow cylindrical extension projecting through said tubular opening, and a spiral spring surrounding said cylindrical extension and holding the valve normally open but allowing it to close when subjected to water-pressure, substantially as described.

2. In a filter, a metallic case and a filtering medium contained therein, a tube leading from the water-supply to a chamber below said filtering medium, an outlet leading from a chamber above said filtering medium, an outlet leading from the lower chamber, and a valve for closing said lower outlet, a thumb-ring carried on a downwardly-extending projection from said valve and a spiral spring surrounding said extension and serving to open said valve when released from water-pressure in the filter, substantially as described.

3. In combination with a filter a slotted sleeve adapted to clamp the end of a water pipe or faucet slightly above its extremity, a screw-thread on the lower portion of said sleeve, a tube having an inner screw-threaded portion to engage such sleeve and having a shoulder just below said screw-threaded portion, and a ring washer resting in said shoulder and adapted to be clamped against the end of the nozzle when the tube is screwed onto the sleeve.

4. In a filter, a metallic case, a filtering medium consisting of a mass of raw cotton contained therein, a centrally-disposed tube leading from the water-supply through said filtering medium to a chamber below, two washers of silk cloth surrounding said tube, one on each side of said filtering medium, a screen of wire-gauze for holding each of said silk

washers against said filtering medium, a tube leading from the chamber above said filtering medium, an outlet leading from the chamber below said filtering medium, and a valve 5 for closing said lower outlet while under water-pressure, but adapted to open when said pressure ceases whereby the water and residue in the lower chamber are automatically

drawn off after each use of the filter, substantially as described.
